SHUTTLE CHECK AND RELEASE FOR
DROP BOX LOOMSElliot A. Santon, Worcester, Mass., assignor to
Crompton & Knowles Loom Works, Worcester,
Mass., a corporation of Massachusetts

Application July 19, 1934, Serial No. 736,054

16 Claims. (Cl. 139—187)

This invention relates to improvements in shuttle checking and releasing devices for looms and it is the general object of the invention to provide means for effectively checking the shuttle as it enters the box and thereafter relieving pressure on it so that it may be picked with a minimum of power.

In certain classes of heavy slow running looms as heretofore constructed the shuttles could be checked by a form of binder which exerted comparatively little pressure on the side walls of the shuttle. When looms of this type are operated at increased speeds, however, the former means for stopping a shuttle are found to be inadequate inasmuch as they permit rebounding and subject the picker to an increased blow when absorbing the momentum of the shuttle. It is an important object of my present invention to provide an improved form of quickly adjustable check which will effectively stop the shuttle when the loom is operating at a high rate of speed and thus prevent undue wear of the pickers.

It is a further object of my invention to provide each cell of a gang of shifting shuttle boxes with its own form of adjustable tension for the binder so that the boxes may be free to shift without hindrance from an outside source. In this connection I arrange a pressure relieving device to overpower the tension device of the cell which is opposite the race at the time of picking. This latter result I accomplish by a mechanism operated from the crank connector.

It is a further object of my invention to provide an improved type of binder having a gradually inclined surface along which the advancing nose of the shuttle slides when the shuttle is being boxed and having at the outer end thereof a comparatively short holding surface which is pressed against the shuttle when the latter is inactive to keep the same from working inwardly toward the cloth. The short surface referred to is close to the shuttle tension relieving device and is moved away from the shuttle just prior to the time of picking so that a minimum of pressure transmitted through the picker will suffice to propel the shuttle across the loom.

My invention further relates to a form of binder construction which permits floating support of the binder together with means to move the binder away from the shuttle.

With these and other objects in view which will appear as the description proceeds my invention resides in the combination and arrangement of parts hereinafter described and set forth in the claims.

In the accompanying drawings, wherein a convenient embodiment of my invention is set forth,

Fig. 1 is a front elevation of the shifting shuttle box end of a loom having my invention applied thereto,

Fig. 2 is a top plan view of the structure shown in Fig. 1,

Fig. 3 is an end elevation of Fig. 1, with certain parts in section and other parts removed for the sake of clearness,

Fig. 4 is a perspective view of the binder,

Fig. 5 is a diagrammatic plan view of the binder showing the relation of the same to the shuttle, and

Fig. 6 is a detail perspective view of the upper end of a control arm for the binders.

Referring particularly to Figs. 1 and 2, I have shown a loom frame 10 having a lay 11 driven back and forth by means of a connector 12. As shown more particularly in Fig. 3 the connector 20 has a head 13 pivotally connected as at 14 to the lay and has upper and lower spaced rods 15 and 16, respectively, around which lie compression springs 17. The crank shaft 18 has a crank arm 19 to which is yieldingly attached the rear end 25 of the connector. The crank shaft is given a rotation for each pick or beat of the loom and as the crank arm swings around the axis of the shaft the rods 15 and 16 will rise and fall relatively to the lay and the shaft. The connector may be made as set forth more fully in Hillman Patent No. 1,323,391.

As set forth herein the loom is adapted for weaving four different colors by means of as many shuttles which are held in the box structure B 35 having cells 20, 21, 22 and 23, respectively. The box structure is provided with ears 24 through which project a vertical binder pin 25 located in front of the binders 26.

A protector finger 30 is adjustably attached to 40 a protector rod 31 which has secured thereto a dagger 32 and is surrounded by a protector spring 33 the normal effect of which is to press the finger 30 backwardly, or toward the binder which is opposite the shuttle race 35 of the lay.

A box rod 37, operated by any approved form of box motion, is the means by which the gang of boxes B is raised or lowered so that any one of the four cells can be placed in active position relatively to the shuttle race 35 at the time of 50 picking.

The matter thus far described is of common construction and of itself forms no part of my present invention.

In carrying my invention into effect I provide 55

a rocking shaft 40 which is movable in outer and inner bearings 41 and 42, respectively, secured to the lay. The inner end of the rocking shaft has an arm 43 secured thereto and this arm extends rearwardly and has a laterally offset finger 44 extending between rods 15 and 16 and is adapted more particularly for engagement with the lower rod 16. If desired a spring 45 may be used as shown in Fig. 3 to hold the arm 43 down, although I have found in practice that the spring is not essential and may be omitted.

Near the outer end of shaft 40 I adjustably secure a second arm 50 extending upwardly and having a head 51 which as shown in Fig. 2 is provided with outer forwardly facing upper and lower inclines 52 and 53, respectively, and has upper and lower rearwardly facing inclines 54 and 55 which are inclined oppositely to the other inclines, as shown in Fig. 6.

Each binder 26 may include in its construction a front sheet metal strip 58 to which is secured a block of wood 59 having a rear leather or friction surface 60. As shown particularly in Fig. 5 the rear surface may have a gradual incline 61 which extends outwardly and rearwardly from the inner end thereof and merges with a substantially straight but short surface 62 near the outer end of the binder. If desired I may incline the extreme left end of the leather surface 30 as shown in Fig. 5 outwardly and forwardly as at 63.

The strip 58 has a U-shaped bend 65 which defines a vertical slot 66 and said strip is then bent outwardly and back on itself as at 67 and 35 then forwardly as at 68, terminating in a lateral bend 69 which extends inwardly toward the center of the loom at a distance spaced forwardly from the body of the strip. The parallel leaves at the bend 67 can be welded together if desired. 40 A vertical pin 70 corresponding to pin 25 extends downwardly through the several cells of the gang of boxes and through all of the vertically aligned slots 66.

Each binder has associated therewith a binder spring 72 secured to the shuttle-box structure and substantially U-shaped. The front part of each spring has a free end bent inwardly toward the center of the loom to have extending adjustably therethrough a pressure screw 73 with a head 74 45 and lock nut 75. The head 74 engages the adjacent binder end 67 and exerts a pressure which can be varied by changing the setting of the screw 73 with respect to the binder spring.

Prior to boxing of a shuttle moving toward the 55 shifting boxes the connector rod 16 will be moving downwardly and will assume its lowest position approximately at the time the shuttle enters the cell opposite the race. Spring 72, acting through screw 73 and binder end 67, yieldingly holds the binder in rear position, with stop pin 70 in the forward part of the slot 66. As the shuttle enters the box its advancing nose will strike the surface 61 and rock the binder in a clockwise direction around pin 70 as viewed in 60 Fig. 2, thereby pushing the protector finger 30 against the action of spring 33 to permit continued running of the loom. As the nose continues along the surface 61 the binder will be wedged outwardly and the pressure binder end 67 will be forced against the screw 73, thereby bending the binder spring which in turn resists outward movement of the binder.

As the shuttle nears the end of its travel it will engage the substantially straight section 62 and 75 will then strike the picker 80 with a very much

reduced blow due to the fact that the major part of its momentum has been absorbed by the binder. The shuttle is therefore boxed against the relatively heavy resistance of the associated binder spring 72.

During the upward swing of the connector rod 16 as the lay approaches picking position, said rod will engage offset 44 and rock arm 43 in a counter-clockwise direction as viewed in Fig. 3 to move the head 51 forwardly or to the left as 10 viewed in that figure. As seen in Fig. 2 the surfaces 52 and 53 are relatable to the bend 69 of the binder and as the head moves forwardly under action of the rising connector the binder end 67 will be given a slight forward movement to relieve the pressure of the shuttle so that it can be picked, the binder being held back merely by the pressure of the comparatively light protector spring 33.

It is to be understood that the binder springs 20 of the shuttles which are inactive and therefore out of alignment with the shuttle race are not affected by the head 51 and such shuttles are therefore held tightly in their boxes so that they will not creep inwardly toward the cloth even 25 though kept idle for a considerable period. As the lay moves rearwardly after picking the connector will move downwardly and the binder spring of the active box will return its binder to normal position before the shuttle again returns 30 to the box. The shuttle is therefore subjected to the full effect of the spring 72 of the box which it is entering.

If after the boxing of a shuttle in one of the cells the pattern calls for a shift of the boxes, 35 this shift will occur and be practically completed before the head 51 engages the binder of the shuttle next to be active. Should the box shift be slow, however, and the head has started to move forwardly before the called box is in active position, one or the other of the inclined surfaces 52 40 or 53 will ease the action of the head with respect to the end 69 of the box becoming active.

The wooden block 59 of the binder prevents the operator from bending the steel part and requires 45 the setting for adjustments to be obtained by changing the binder spring.

By the use of a binder release I am able to pick the shuttle across a loom of given width, running at a given rate of speed, quicker than by former 50 practice. For this reason it is possible to equip the loom with a slower Knowles head than is standard for the same conditions of width and speed, permitting the use of softer warp and with fewer stops because of warp breakage.

From the foregoing it will be seen that I have provided a simple means for relieving the pressure of the binder of a shuttle box in picking position, the means for accomplishing this result being controlled from the loom connector. It will further be seen that each cell of the gang of 55 boxes carries its own form of shuttle check and that these checks are all independently adjustable with respect to each other, and each is subject to the overpowering effect of the head 51 just prior to picking. I have found by reason of the set screw 73 and check nut 75, shown particularly in Fig. 2, that adjustments of the binder pressure against the shuttle can be very easily varied. It will also be seen that the binder of each of the 60 cells of the shuttle box floats and is subject to the action of two springs, one the comparatively light protector spring 33 and the other the comparatively heavy binder spring 72. The latter is not deflected until the binder has been moved. 65 70 75

outwardly against the pin 25. After the shuttle has moved a substantial distance along the inclined surface 61 with the metallic strip 58 against the pin 25, the light spring 33 of the protector has 5 no further effect on the shuttle checking and this fact simplifies the adjusting of the pressure to be exerted by spring 72.

Having thus described my invention it will be seen that changes and modifications may be made 10 therein by those skilled in the art without departing from the spirit and scope of the invention and I do not wish to be limited to the details herein disclosed, but what I claim is:

1. In a loom having a lay, a gang of shuttle 15 boxes, a substantially U-shaped spring for each shuttle box of the gang, one end of each spring secured to the gang and the other end extending toward the inner end of the binder, a binder for each shuttle box having a projection extending 20 into the corresponding U-shaped spring, and adjustable connections between said other end of each of said springs and the corresponding extension to exert a variable force derived from the spring against the extension to vary the shuttle 25 checking force exerted by the binder.

2. In a loom having a lay, a gang of shuttle 30 boxes, a binder for each shuttle box, a protector finger to exert a comparatively light pressure on the inner end of the binder and the shuttle in active position, means to provide for moving the outer end of the binder bodily and transversely of the shuttle box and means for each shuttle box to exert on the outer end of the binder a yielding force greater than the force exerted by 35 the protector finger, whereby boxing of the shuttle will move the protector finger before moving the outer end of the binder.

3. In a loom having a lay, a gang of shuttle 40 boxes, a binder for each shuttle box, a protector finger to exert a comparatively light pressure on the inner end of the binder and the shuttle in active position, means to provide for moving the outer end of the binder bodily and transversely of the shuttle box, means for each shuttle box to exert on the outer end of the binder a yielding force greater than the force exerted by the 45 protector finger, whereby boxing of the shuttle will move the protector finger before moving the outer end of the binder, and means operative prior to 50 picking to lessen the force exerted on the outer end of the binder corresponding to the shuttle in active position.

4. In a loom having a lay, a shuttle box thereon, a binder for the shuttle box, a protector finger 55 exerting a relatively light pressure on the inner end of the binder moving the latter toward shuttle checking position, means defining a sliding guide transversely of the box for the outer end of the binder, and resilient means tending to move the outer end of the binder along the guide with a yielding force greater than that exerted by the 60 protector finger.

5. In a loom having a lay, a shuttle box on the 65 lay, a binder for the shuttle box, means on the outer end of the binder defining a transverse slot, guide means passing through the slot, a binder spring carried by the box and exerting a force on a portion of the binder adjacent the slot and resisting movement of the binder in an outward 70 direction transverse of the shuttle box.

6. In a loom having a lay, a shuttle box thereon, a binder for the shuttle box, a guide pin, a bracket on the outer end of the binder defining a slot through which the pin passes and defining 75 also an extension, a U-shaped spring secured to

the box and disposed to receive the extension, and an adjustable pressure screw carried by the spring and bearing against the extension and tending to cause movement of the bracket relatively to the pin, the latter resisting movement of the binder lengthwise of the shuttle box and guiding said binder when the latter moves transversely of the box. 5

7. In a drop box loom, a set of shifting shuttle 10 boxes, a binder for each box having a bracket with a lateral bend, and a binder controlling arm having a rearwardly convex surface to engage the binders as the boxes shift and having also a forwardly convex surface to engage said bends when the boxes shift. 15

8. In a loom, a set of shifting shuttle boxes, a binder for each box, yielding means for each binder to hold the latter in shuttle checking position, withdrawing means related to each binder by which the latter can be moved against the 20 action of the corresponding yielding means, and a binder control arm having a convex surface to face rearwardly for engagement with the binders and having also a forwardly convex surface to engage the second named means, said convex 25 surface capable of sliding engagement with the binders and their withdrawing means as the boxes shift.

9. In a loom having a lay with a shuttle box, a 30 binder, means defining a sliding connection between the shuttle box and the binder extending in a direction transversely of the box, yielding means acting on the binder adjacent the means to move the latter rearwardly toward the center of the box, and means operative at a given time in the cycle 35 of loom operation to move the binder outwardly from the box against the action of the yielding means.

10. In a loom having a lay with a shuttle box, 40 a binder the inner end of which is movable in a direction transversely of the box, means defining a sliding connection extending transversely of the box between the outer end of the binder and the shuttle box, yielding means normally tending 45 to move the outer end of the binder toward the center of the box, and periodically acting means operatively related to the outer end of the binder to move the same transversely of the box and away from the center thereof.

11. In a loom having a lay with a shuttle box, 50 a binder the inner end of which is movable transversely of the box, means defining a pin and slot connection extending transversely of the box between the outer end of the binder and the box, yielding means tending normally to move the outer end of the binder bodily toward the center of the box, and periodically acting means operatively related to the outer end of the yielding 55 means to move the latter away from the center of the box. 60

12. In a loom having a lay with a shuttle box, 65 a binder, means defining a sliding connection between the shuttle box and the binder extending in a direction transversely of the box, yielding means acting on the binder adjacent the means to move the latter rearwardly toward the center of the box and means operative at a given time in the cycle of loom operation to overpower the yielding means and render the latter ineffective 70 to move the outer end of the binder toward the center of the box.

13. In a loom having a lay with a shuttle box, 75 a binder the inner and outer ends of which are movable bodily transversely of the shuttle box, a

- protector finger exerting a relatively light yielding pressure on said inner end of the binder tending to move the latter toward the center of the box, and yielding means exerting a relatively high pressure on the outer end of the binder tending to move the same toward the center of the box, entry of a shuttle into the box causing the inner end of the binder to move outwardly to move the protector finger before moving the outer end of the binder away from the center of the box.
14. In shuttle checking means for a loom having a lay carrying a shuttle box, a binder for the shuttle box, means adjacent the outer end of the shuttle box defining a sliding pivotal connection between the shuttle box and the bobbin and extending transversely of the box, an extension on the binder projecting outwardly beyond the sliding pivotal connection, and yielding means carried by the shuttle box and effective to exert a force on the extension tending to move the outer end of the binder transversely of the shuttle box.
15. In a loom having a lay provided with a shuttle box, a binder the inner end of which is movable transversely of the shuttle box, means defining a transverse slot in the outer end of the
16. In a loom having a lay with a shuttle box, a binder the inner end of which is movable transversely of the shuttle box, means on the outer end of the binder defining a slot extending transversely of the shuttle box, pivot means on the box extending into the slot, an extension on the outer end of the binder projecting beyond the slot, and yielding means exerting a force on the extension tending to position the slot so that the pivot means is normally spaced from the rear end of the slot, said yielding means resisting movement of the outer end of the bobbin in a direction to move the rear end of the slot toward the pivot means.

binder, pivot means secured to the shuttle box extending into the slot, and yielding means to resist movement of the outer end of the binder relatively to the pivot in a direction transversely of the box and away from the center of the latter, the yielding means holding the binder so that the pivot is normally intermediate the ends of the slot, entry of a shuttle into the box moving the binder so that the rear end of the slot moves forwardly into pivoting relation with the pivot means. 10

17. In a loom having a lay with a shuttle box, a binder the inner end of which is movable transversely of the shuttle box, means on the outer end of the binder defining a slot extending transversely of the shuttle box, pivot means on the box 15 extending into the slot, an extension on the outer end of the binder projecting beyond the slot, and yielding means exerting a force on the extension tending to position the slot so that the pivot means is normally spaced from the rear end of the slot, said yielding means resisting movement of the outer end of the bobbin in a direction to move the rear end of the slot toward the pivot means. 20

ELLIOT A. SANTON. 25
